DESIGNS

10-8

Nº 3249

Carl Müllers Design for a Clock Case

PATENTED
NOV 17 1868

Witnesses -

Pno W. Williams
Henry Passy

Inventor

Carl Müller

C A R L M Ü L L E R, O F N E W Y O R K, N. Y.

Design No. 3,249, dated November 17, 1868.

DESIGN FOR A CLOCK-CASE.

The Schedule referred to in these Letters Patent and making part of the same.

To all whom it may concern:

Be it known that I, CARL MÜLLER, of the city, county, and State of New York, have invented a new and useful Design for a Clock-Case; and I do hereby declare that the following is a full, clear, and exact description thereof, which will enable those skilled in the art to make and use the same, reference being had to the accompanying photograph, forming a part of this specification.

This invention relates to a design for a clock-case. For convenience in description, the design may be divided into two parts, a a being the upper or main one, and b b, the base or lower part.

The main features of the whole design are two lads, one in the act of tattooing the other's arm. The one on the left side holds out his left arm, with the sleeve rolled up, ready for the artist. With his right hand, which he has at his breast, he holds a paper, with an anchor, and U. S. marked thereon.

In the background may be seen a common street-hydrant. The fellow on the right has a pencil in his right hand, and a plate, with ink, in his left, trying his best to reproduce the design of the anchor and U. S. on the other's arm. Here, in the background, a post is visible, surmounted by a horse's head. Between the figures is the dial-hole, and above that ornaments, as seen in the photograph.

The central portion of the base, b b, is ornamented by a medallion-head of a youth, on a sort of shield, with the face looking heavenward. On each end of the base is the upper half of a boy holding a dog, in full gallop towards the other, by the tail, one with a sorrowful and the other a joyful face. The lower portion of the base is also embellished by a chain of arabesques, as shown in the photograph.

What I claim as my invention, and desire to secure by Letters Patent, is—

The design for a clock-case, as herein shown and described.

Signed by me, this 16th day of October, 1868.

CARL MÜLLER.

Witnesses:

JNO. W. WILLIAMS,
HENRY RASSIGA.